Primary Examiner—A. Hugo Word*Assistant Examiner*—I. Simmons*Attorney, Agent, or Firm*—Todd A. Dawson**[57] CLAIM**

The ornamental design for a bone milling template, as shown and described.

DESCRIPTION

FIG. 1 is a perspective view of a bone milling template showing my new design;

FIG. 2 is a top elevational view thereof, the bottom elevational view being identical thereto;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view of a second embodiment of a bone milling template showing my new design;

FIG. 8 is a top elevational view thereof, the bottom elevational view being identical thereto;

FIG. 9 is a front elevational view thereof;

FIG. 10 is a rear elevational view thereof;

FIG. 11 is a right side elevational view thereof; and,

FIG. 12 is a left side elevational view thereof.
